WILLIAM C. WHITCOMB AND WILLIAM F. ECKERT, OF ROCHELLE, ILLINOIS, ASSIGNEES TO GEO. D. WHITCOMB COMPANY, OF ROCHELLE, ILLINOIS, A CORPORATION OF ILLINOIS.

SPRING SUPPORT FOR RAILWAY CARS.

Application filed January 6, 1928. Serial No. 244,902.

This invention relates to spring supports for railway cars and has more particular reference to a spring support especially adapted for gasoline locomotives.

5 The primary purpose of our invention is to provide an improved spring support or mounting for a railway car or locomotive which will permit of quick installation and removal of the spring and will eliminate the 10 use of extraneous fastening means and parts.

We have also aimed to provide a side frame structure embodying a spring support in which the side frame is preferably a single piece casting having pedestal jaws and a 15 retaining housing for the spring which serves to support the side frame on the journal box. This single piece side frame provides a rigid and substantial structure and makes for simplicity in design and construction. The side 20 frame and journal box are shaped to retain and hold the spring in operative position without the use of bolts or other fastening devices and are further shaped so that the spring may be quickly removed or installed.

25 Referring to the drawing:

Figure 1 is a side elevation of a locomotive embodying our invention;

Fig. 2 is a vertical section through one of the axles and its spring mounting;

30 Fig. 3 is a vertical section taken substantially on the line 3—3 of Fig. 2.

The locomotive shown in the drawing is of the type propelled by an internal combustion engine and adapted to be used either on a 35 standard or narrow gauge track for general hauling purposes, especially in connection with mining, lumbering, quarrying, road building, and in industrial plants.

The frame of the locomotive is cast to shape 40 and may comprise either one or more parts. In some forms of our invention the sides 4 and bumpers 5 are integral as a one-piece casting and in others the sides and bumpers may be cast separately and suitably bolted together. Our invention has to do with the 45 shape of the side frame in connection with the spring support at each end of each axle. Only a single illustration of the invention is given, showing its application to one of the 50 front springs. It should be manifest, however, that the invention is applicable not only to a locomotive frame and spring support but to any railway car.

The side frame 4 is shaped to provide

pedestal jaws 10 which serve to guide the 55 journal box 6 in the usual manner. The journal box, its axle and wheel may be of conventional construction.

The frame 4 is supported on the journal box through the agency of a half-elliptic leaf 60 spring 7, the leaves of which are held together by a suitable strap or band 8. This strap seats in a recess 9 in the top of the journal box. The spring is thus located and held from displacement in a horizontal plane. 65

The side frame is further shaped to provide a transverse opening 11 of an over-all length greater than the spring and having a recess 12 at each end for reception of the adjacent end of the spring. The side walls of 70 these recesses or pockets serve to retain and hold the spring from lateral displacement. The spring is thus retained in its operative position only by location in the recess 9 in the top of the journal box and by the recesses 75 12 in the frame, the supported weight serving, of course, to hold the spring in this position. It will be manifest, however, that upon raising the frame with respect to the journal box the spring will drop or follow the journal box, thus withdrawing the ends 13 of the spring from the recesses 12 and into registration with the ends 14 of the opening 11. In this position the spring may be withdrawn laterally through the opening 11 or may be 80 inserted in position, as the case may be. The spring support is thus effected without the use of bolts or other extraneous or removable parts. It is obvious that this construction permits of quick removal or displacement of 85 the springs and does not require the use of special tools either in assembly or repair work. 90

We claim:

1. A railway car having an integral side 95 frame providing pedestal jaws and a spring housing, a journal box guided by said jaws, and a half-elliptic spring seated on the journal box and confined at its ends by walled recesses of said housing, the spring being removable laterally from the frame after having been lowered with respect thereto to withdraw its ends from between said recess walls. 100

2. A car frame one side of which is shaped to provide pedestal jaws and a transverse opening above and contiguous to said jaws, a journal box guided by the jaws, a half-elliptic spring seated in a recess in the top of the jour- 105

nal box, the said transverse opening permitting lateral passage of the spring into and out of position above the journal box, the frame being shaped to provide a recess at 5 each end of the said transverse opening for reception of the adjacent end of the spring, the side walls of said recesses holding the spring from lateral displacement.

3. In a railway car, a frame having pedestal jaws and a transverse opening above and contiguous to said jaws, a journal box guided by said jaws, a leaf spring interposed between the journal box and the frame, the frame having recesses in which the ends of 10 the spring are normally confined from lateral displacement and which permit withdrawal of the spring downwardly when the journal

box is lowered with respect to the frame, said spring being removable from the frame laterally through said opening when withdrawn 20 from said recesses.

4. A locomotive frame shaped to provide pedestal jaws, a transverse spring-receiving opening thereabove, and a downwardly opening retaining recess at each end of said opening adapted to receive the end of a half-elliptic spring, the side walls of said recesses serving to retain the spring from lateral displacement, the spring being adapted to withdraw downwardly from said recesses and 25 laterally through said opening.
